GEAR PUMP SEAL

George F. Maglott, Cranston, R. I., assignor to
 Brown & Sharpe Manufacturing Company, a
 corporation of Rhode Island

Application June 2, 1934, Serial No. 728,798

4 Claims. (Cl. 286—7)

This invention relates to a gear pump for pumping liquid, more particularly a liquid having lubricating properties such as fuel oil for oil burners; and has for one of its objects the provision of a seal which will both prevent the escape of the oil from pressure developed on the inside of pump and prevent any suction developed within the pump from drawing in air.

Another object of the invention is the provision of a seal which will be unaffected by the running out of line of the drive shaft for driving the pump.

Another object of the invention is the provision of a common means which will assist the seating of the seal against pressure developed in the pump and also assist the seating of the seal against suction developed in the pump.

Another object of the invention is the circulation of the lubricant about the moving parts and yet maintaining a seal of the lubricant in the pump casing.

Another object of the invention is the provision of a circulation of the material pumped in such a manner that it will lubricate the moving parts in a small pump by arranging certain of the conduits for the lubricant through the moving parts as distinguished from through the fixed part of the casing itself.

Another object of the invention is to cause the lubricant circulation to assist in taking from the pressure seal some of the pressure which might otherwise be caused to be exerted thereon and thus reduce a chance of leakage through this seal.

Another object of the invention is the arrangement of the parts so as to maintain a hydrostatic balance of pressure on both sides of the pumping elements.

A further object of the invention is the provision of a pump the parts of which are the same regardless of the direction in which it is to operate which may be elected in finishing by merely choosing the arrangement of certain of the formed openings therein.

With these and other objects in view, the invention consists of certain novel features of construction, as will be more fully described, and particularly pointed out in the appended claims.

In the accompanying drawing:

Fig. 1 is a sectional view through the pump;

Fig. 2 is a sectional view on line 2—2 of Figure 1;

Fig. 3 is a sectional view on line 2—2 of Figure 1;

Fig. 4 is a perspective view showing some of the

parts fragmentally and the arrangement of my novel sealing unit and drive transmission between the drive shaft and one of the pumping elements;

Fig. 5 is a perspective view of the pump looking at the outside thereof and also illustrating a modified construction with reference to that illustrated in Figures 1 and 2.

In the operation of liquid gear pumps, there has been considerable difficulty in maintaining a proper seal about the drive shaft which extends through the casing and operates one of the gears. If this seal were not tight when pressure of the liquid is developed in the pump, the liquid will be forced out about the drive shaft, whereas if the pump were not tight when there is a suction developed in the pump casing, air will get in. With a small bubble of air in the pump, the pump will hammer and knock and run noisy for a considerable length of time. This seal is often caused to be imperfect by reason of the wobbling or the getting out of line of the drive shaft to which the seal is frequently attached, and in this case I have provided a seal which is independent of the alignment of the drive shaft so that should the drive shaft be out of true line, the seal will be effectual to maintain the seal in the pump.

Also, there must be some means provided for lubricating the operating parts of a gear pump of this character. Frequently, the liquid which is to be pumped is of a lubricating quality, such for instance as the pumping of oil and where this is the case, as in the uses for which the present pump is particularly designed, a circulation is provided of this liquid about the moving parts so that fresh liquid is continually supplied to these parts to afford a more perfect lubrication rather than a stagnant lubrication which occurs in some pumps, in which case the oil will lose some of its lubricating properties and permits heating within the pump.

Sometimes in pumps of this character where there is a circulation of the oil, the oil is extruded out of the pump and lost, whereas this invention contains the oil at all times in the pump and seals it against escape.

Also, in small pumps it is rather difficult to provide a sufficient amount of stock for the formation of a conduit for the lubricant, and in order to economize space, I have provided a channel through the drive shaft which operates the gears of the pump and by which a very efficient circulation is provided, and I have so arranged the circulation of the liquid in the pump that it cooperates with the seal to effect a more

complete seal by relieving pressure on the seal during the running of the pump.

Further, by my arrangement and transmission of pressures, I maintain a hydrostatic balance in the pump on both sides of the pumping elements; and the following is a more detailed description of the present embodiment of this invention, illustrating the preferred means by which these advantageous results may be accomplished:

- 10 With reference to the drawing, 10 designates the body section of the pump, which is provided with an opening housing the gears 11 and 12, which mesh together and about which there is left a suction pocket 13 and a pressure pocket 14 for the entrance and delivery of the liquid to be pumped. At either side of the body element, I provide cap sections or closure members in one of which there is located suitable discharge and suction conduits.
  - 15 One end cap section is designated 15, and the other end cap section 16 which also has formed therewith a bracket portion 17 in which the sealing and driving means are largely mounted. The cap sections 15 and 16 are held assembled on either side of the body section 10 by suitable bolts 18 and 19 extending through one of the cap sections, through the body section and threaded into the other cap section, whereby the sections are held in assembled relation sufficiently tight so that there will be no leaking of air into or pumping of the liquid out of the casing.
  - 20
  - 25
  - 30

Pumping elements or gears 11 and 12 may be made integral with or mounted on shafts 20 and 21 to which they may be securely fixed against relative rotation. These shafts have bearings in the opposite cap sections; thus shaft 20 has a bearing 22 in the cap section 15, and 23 in the cap section 16, while the shaft 21 has a bearing 24 in the cap section 15, and 25 in the cap section 16.

In this particular embodiment of the invention, the suction conduit 26 and discharge conduit 27 are provided in the cap section 15, the former communicating with the suction pocket 13, while the discharge conduit 27 communicates with the pressure pocket 14. Suitable connection may be had to these conduits by means of the threaded bores 28 and 29 for the intake and delivery of the liquid to be pumped.

50 The gear or pumping element 11 is driven through its shaft 20 by means of a drive shaft 30 which is connected to the shaft 20 through a sealing means which consists of a disc 31 and a disc 32, each provided with tongues 33 and 34, which fit into slots 35 and 36 in the coupling member 37, there being a helical spring 38 encircling the coupling member and engaging the inner surfaces 39 and 40 of the discs tending to force them apart. The sealing unit is rotatably mounted in a bore 41 in the portion 17 of the cap section 16, the end of this bore being provided with a finished seat 42 against which the finished surface 43 of the disc 31 engages to form a seal, the disc being of a size substantially that of the bore 41 to be guided in its rotation in this bore.

A sleeve 44 is inserted into the bore 41 to an extent to retain the helical spring 38 under compression, and the tongues 33 and 34 in their respective slots 35 and 36, although not sufficient to force the discs into firm engagement with the coupling member 37. The inner end 45 of this sleeve 44 provides a finished seat against which the finished surface 46 of the disc 32 engages to form a seal. The disc 32 is also of a size to be guided in its rotation by the bore 41. The sleeve

44 is provided with a flange 47 at its outer end, and is held in position by suitable bolt 48.

The sealing unit is connected to the shaft 20 by a key 51 entering a slot or recess 49 in the shaft 20, and slot or recess 50 in the disc 31, and of a length and size to more or less loosely fit therein and yet maintain its driving position. Thus any rotation of the sealing means will cause a rotation of the shaft 20 while allowing the shaft 20 to be entirely independent of the sealing means so that any irregular running of the parts within the pump need not rock the seal from its seat.

The sealing means is driven through the tongue 52 on shaft 30 extending into the slot or recess 53 in the disc 32. This slot is sufficiently large so 15 that there may be a rocking of the shaft 30 in the slot and any irregularity in alignment with the shaft 30 will not be communicated to the disc 32 and thus accurate alignment of the shaft or 20 true running in its bearings is not essential to the maintaining of this seal in its operating or 25 working position. The shaft 30 is bushed as at 54. Oil is fed to the bearing through the opening which is closed by a set screw 55 to keep out foreign matter. A shoulder 56 fixed on the shaft 30 is engaged by a plate 57, which plate is held 25 in place by reason of bolts 48 and which in turn serves to secure the sleeve and bushing in place on the portion 17 of the cap section 16.

Should any pressure be exerted on the sealing means from the inside outwardly and liquid be forced by the first disc 31, then the second disc 32 would be forced more tightly to its seat by the addition of such pressure assisted by the spring 38, and thus from the inside provide a tight seal between the surfaces 45 and 46. Such pressure might occur from a head existing in the storage tank when the pumping elements are not rotating. It is also of importance that the seal be maintained against a low pressure developed in the pump from drawing in air due to a greater pressure outside, and in this case, the reverse will be true in that any air entering about the shaft 30 may pass the first disc 32, but this outside pressure will be exerted against the surface 39 of disc 31 to force the disc 31 more firmly to its seat, also assisted by spring 38, and thus effectively prevent entrance of air into the pump, which might cause it to knock. Thus, this spring acts in both directions to assist in preserving the seal in the pump, while both discs are unaffected by any of the operating parts which is very often detrimental to pumps of this character.

This particular pump is designed for pumping oil a liquid having lubricating properties and utilization may be made of the liquid for the lubrication of the moving parts of the pump, and I have taken advantage of this by providing certain channels to maintain a circulation of the liquid to be pumped about the bearings for the shafts 20 and 21. In the casing, I have provided a conduit 60 which, as shown in Figure 1, is formed in the cap section 16 and extends upwardly from the pocket at the end of shaft 21 to connect with the pocket at the end of the other shaft 20, and in fact, in order that I may provide such a conduit, I have drilled the casing from the outside and then blocked up the outer end of this conduit as at 61. I have also provided conduits or openings 62 through the shaft 20 and a conduit 63 through the shaft 21, also a conduit in the casing from the left hand end of the shaft 20 to the suction chamber 13, which conduit I designate 64. By this arrangement, any liquid which seeps into bearing 24 from the gear 75

12, will work its way along this bearing to the pocket 65 at the end of shaft 21, thence through the hole 63 in the shaft 21 to the pocket 66 at the opposite end of this shaft, thence through conduit 60 to and through the hole 62 and out through the conduit 64 to the suction chamber 13 of the pump. Any liquid working into the bearing 25 will be conveyed to the chamber 66 through conduit 60, hole 62, and to the suction conduit 64. Any liquid working into the bearing 23 will be conveyed to the end of the shaft and thence through a hole 62 to this conduit 64, while any liquid working into the bearing 22 will be conveyed to the pocket 68 which directly connects with conduit 64 and thus to the suction chamber. Thus it will be seen that all the bearings are connected to the suction side of the pump, and any liquid leaking in from the pressure side will be drawn back to this suction side, 20 and there will be provided a continuous circulation of liquid about these bearings in the chamber.

A chamber or pocket 69 at the right hand end of shaft 20 is in communication with the port 64 and the suction chamber, and thus there is a continual moving of any liquid from this pocket 69 towards the suction side of the pump and away from the disc 31, and the continual movement away from this disc tends to lessen the pressure on the disc, and thus this circulation assists in relieving any pressure in the pump tending to force any liquid out of the pump.

Further, by my means of the arrangement of parts and circulation above mentioned, I maintain a perfect axial hydrostatic balance of pressures on either side of each of the pumping elements. Each area is fully balanced both on the pumping elements or gears themselves, as well as the pressures on the shafts 20 and 21, and thus this 40 pump will operate a far greater length of time by reason of this balanced pressure than where the pressure is greater on one side of the pump element than on the other, forcing it towards some surface which must receive the thrust communicated to it.

Another feature of the present construction is that by the use of the same gears and the same castings, I may provide a pump which may be arranged to run in a right or left hand direction, 50 although the chosen direction must be determined before the pump is finished, as I must of necessity place the bore 64 on one side or the other, depending upon the direction the pump is to be run; for instance, in Figure 2, the suction conduit is said to be 26 and the bore 64 must connect the bearing 22 with the suction side of the pump, thus if I desire to change the direction of rotation of the pump elements, it will be necessary for me to connect this bore 64 with 55 the opposite conduit 27, but as this is merely a drilling operation on the opposite side of the cap member, the identical casings may be used regardless of the direction of rotation of the pump.

I also may optionally provide a suction and pressure conduits in the cap section 16, as I have illustrated in Figure 5, instead of in the cap section 15. Thus I may select from several of optional forms of construction without any material changes of construction.

The foregoing description is directed solely towards the construction illustrated, but I desire it to be understood that I reserve the privilege of resorting to all the mechanical changes to which the device is susceptible, the

invention being defined and limited only by the terms of the appended claims.

I claim:

1. In combination, a casing provided with a bore and a pair of opposed end seats, a shaft rotatably mounted in said casing, a drive shaft rotatably mounted in said casing and extending along said bore in a direction towards the first shaft but terminating short of said shaft to leave a space therebetween, and sealing drive means through which said drive shaft and the other shaft are connected, said sealing drive means being interposed entirely between the ends of said shafts and comprising a pair of movable discs in engagement with said seats, a coiled spring between said discs for exerting pressure in opposite directions against said discs to force them into sealing engagement with said seats, tongues on said discs, and a coupling member having slots to receive said tongues on the discs and located with- 10 in and axially of said spring for connecting said discs for the transmission of rotation from one to the other.

2. In combination with a casing provided with an elongated cylindrical bore having a pair of opposed seats, of a shaft rotatably mounted in said casing and provided with a tongue extending in said bore, a drive shaft having a tongue and rotatably mounted in said bore, said drive shaft extending along the bore of said casing in a 25 direction towards the first shaft but terminating short of said shaft to leave a space therebetween, and sealing drive means through which said drive shaft and the other shaft are connected for rotation, said sealing drive means being an 30 independent unit entirely disposed between the ends of said shafts and comprising a pair of discs in engagement with said seats and of such size as to be guided in rotation by said bore, a helical spring mounted between said discs and axially 35 thereof for exerting pressure in opposite directions against said discs to force them against said seats, tongues on said discs, and a coupling member having slots to receive the tongues of said discs, said member being axially located with- 40 in said spring for connecting said discs for the transmission of rotation from one to the other, said discs having outwardly facing slots to receive the tongues provided on said shafts for the transmission of rotation from one shaft to another. 45

3. The combination with a casing having an elongated cylindrical bore therein within which is contained a pair of opposed annular seating surfaces, of a shaft rotatably mounted in said casing and extending into said bore, a drive shaft 55 in axial alignment with said first shaft, said drive shaft being rotatably mounted in said casing and extending inwardly along said bore towards the first shaft but spaced therefrom, and sealing drive means within said casing in axial alignment with 60 said shafts and interposed between the ends of the latter for transmitting rotary motion, said sealing drive means comprising a pair of longitudinally movable discs having tongue and groove driving connection with the ends of said shafts and between which said discs are solely movable for longitudinal movement, a coupling member having tongue and groove driving connection with said discs and co-axial therewith, and a coiled spring surrounding said coupling and interposed 65 between the inner end faces of said discs for constantly exerting endwise pressure upon said discs to move them in opposite directions and into sealing engagement with the said casing seats.

4. In a device of the character described, the 75

combination with a casing having an elongated cylindrical bore therein the inner end wall of which is provided with an annular seating surface and a shaft opening, of a shaft extending through said opening into said bore and terminating close to said seating surface, a sleeve within said bore and having an end seating surface thereon, a drive shaft journaled in said sleeve and in axial alignment with said first shaft, said drive shaft extending inwardly along said bore towards said first shaft but spaced therefrom, and a sealing drive device within said bore and comprising a pair of spaced longitudinally movable disc members having a coupling sleeve interposed therebetween, said drive device being arranged in axial alignment with said shafts and entirely

interposed between the ends of the same for transmitting rotary motion, said discs being of such size as to be guided by the bore in their rotation therein, said discs having a sealing surface on their outer ends, one of which is adapted to engage the seating surface of the inner wall of said bore and the other to engage that on the end of said sleeve, a coiled spring surrounding said coupling and interposed between the inner end faces of said discs to exert endwise pressure for forcing the discs apart and in sealing engagement with said seating surfaces, said discs having tongue and groove driving connection with said coupling and said shafts.

15

GEORGE F. MAGLOTT.
